[57] **CLAIM**

The ornamental design for a housing for a video terminal display unit, substantially as shown and described.

DESCRIPTION

FIG. 1 is a perspective view of a housing for a video terminal display unit embodying my new design;

FIG. 2 is a view from the front thereof;

FIG. 3 is a view from the right side thereof;

FIG. 4 is a view from the left side thereof;

FIG. 5 is a view from the rear thereof; and

FIG. 6 is a view from the top thereof.

The broken lines representing the keyboard are shown for illustrative purposes only.

FIG. 2

FIG. 4

FIG. 1

FIG. 3

FIG. 5
